The ornamental design for an aromatherapy machine, as shown and described.

DESCRIPTION

FIG. 1 is a front, top perspective view of an aromatherapy machine, showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged detail view of area 9 circumscribed in FIG. 3.

The evenly spaced broken lines depict portions of the aromatherapy machine that form no part of the claimed design.

The short-short-long dashed broken lines immediately adjacent to the claimed surface in FIGS. 1 and 7 show the bounds of the claim and form no part thereof.

The dash-dot-dash broken lines denote the boundaries of the enlarged detail view areas and form no part of the claimed design.
